UNITED STATES PATENT OFFICE

JOHN GLEN NEWMAN, OF DARLINGHURST, NEW SOUTH WALES, AUSTRALIA

MANUFACTURE OF MATCHES

Application filed June 6, 1929, Serial No. 368,978, and in Australia January 10, 1929.

This invention relates to improved methods and improved means for manufacturing matches from paper pulp board or the like, and has been devised to produce a more efficient match, to increase the rate of production, to simplify the mode of construction and to reduce the cost of manufacture.

In accordance with the invention matches are formed as flat strips projecting in the same plane from a butt or stub and headed with striking material on one or on both broad faces of the strips as desired. Each strip is reinforced longitudinally and coated with paraffin or the like to promote burning and is perforated near the butt to facilitate removal from the butt.

Individual machines have been used to perform one of the operations of cutting, dipping, perforating, heading, and staggering, without regard to uniformity of rate of production, batches of treated material from each machine being stacked awaiting operation by the next machine. In my invention, however, to avoid delays and over-production by one or more separate machines, and to eliminate unnecessary stacking and handling between the machines I form a complete working unit in which the individual operating parts are assembled in line with each other on a common base plate, driven at the same rate preferably from one driving shaft, and receive in turn the treated material as it leaves the prior operating part so that all the operative parts function at the same time and rate and assist to feed each other in successive order.

In the accompanying drawings, which illustrate one form of match-making means and two forms of matches:

Fig. 1 is a side elevation of portion of the apparatus.

Fig. 2 is a similar view of the remaining portion.

Fig. 3 is an enlarged sectional view of portion of the splitting rollers.

Fig. 4 is a perspective view of portion of one splitting roller.

Fig. 5 is a front elevation of crowning and ribbing rollers.

Fig. 6 is a sectional side elevation of a dipping well and accessories.

Fig. 7 is a front elevation of perforating rollers.

Fig. 8 is a sectional side elevation of guide plates.

Fig. 9 is a sectional view of a heading block.

Fig. 10 is a similar view of another form of heading block.

Fig. 11 represents front and sectional elevations of one form of match.

Fig. 12 represents front and sectional elevations of another form of match.

Fig. 13 is a front sectional elevation of portion of a staggering wheel.

Fig. 14 is a side sectional elevation of the same.

The front or feeding end of the apparatus is provided with feeding rollers 20, 21, the roller 20 being driven by means of a belt 22 and pulley 23 from any suitable power source.

Beyond the feeding rollers and in line therewith are mounted splitting rollers 24, 25. The working face of each roller is formed with flat ended straight edged teeth 26 of rectangular section, the recesses between the teeth 26 being filled with rubber blocks 27 faced with metal plates 28 which are secured to the blocks by pins 29 and form portion of the periphery of a roller. The rollers are so adjusted that the teeth of one roller project slightly into the recesses between the teeth of the other roller.

Shaft 30 of roller 24 is carried near each end in a bearing block 31 which is adapted to be raised or lowered in a frame 32 by means of a threaded shaft 33 and handwheel 34. A set screw 35 serves to lock the shaft 33 in any desired position.

Roller 24 is driven from the shaft of feeding roller 20 by means of an idler wheel 36 which meshes with a pinion on shaft 30.

A brush 37 revolved by a belt 38 is applied to clean roller 25.

Beyond the splitting rollers are mounted crowning and ribbing rollers 39, 40. The roller 39 is driven from the shaft of roller 20 in a manner similar to that of roller 24 by pinions and an idler wheel 41.

The face of roller 39 is provided with a circumferential row of curved recesses 42 and with a series of transverse recesses 43. These recesses are positioned to register with a row of removable curved bosses 44 and transverse ribs 45 on roller 40 in order that a crown and a reinforcing rib may be formed on each match strip as it passes between the rollers.

10 A dipping well 46 containing liquid paraffin or the like inflammable liquid maintained at a desired temperature by means of an electric heating element 47 and a perforated guide plate 48, is positioned behind rollers 39, 40. The level of the liquid in the well is maintained by a float valve 49 of ordinary construction which controls the supply of liquid through a pipe 50. An idler wheel 51 is slidably mounted above the well with its lower edge near the guide plate 48.

Beyond the well are mounted perforating rollers 52 and 53. Roller 53 is provided with a circumferential groove 54 and is adapted to be rotated from the shaft of roller 20 by bevel wheels 55, 56 and a connecting shaft 57. Roller 52 is fitted with a row of perforating pins 58 which project into the groove 54.

A heading device is mounted beyond the perforating rollers and comprises a block 59 slotted on its lower face and recessed to receive the match strip heads, adjustable plates 60 and 61 to prevent leakage of heading material, and a valve controlled tank 62 of heading material which is kept at the desired temperature by means of a water jacket 63 heated by an electric heating element 64. A delivery passage 65 in the block communicates with the tank and the vertically adjustable plate 61 serves as a gauge to regulate the amount of material to be left on each match head. A spring loaded plate 66 is provided to seal the slot and recess in the block.

To assist the travel of a ribbon of paper pulp board through the operating devices feeding rollers 67, 68, driven by means of pinions and idler wheels in a similar manner to that set out for roller 24, are mounted in the line of travel between the perforating rollers and the heading device. Guide plates (Fig. 8) having an adjustable upper plate 69 projecting over the end of the ribbon are positioned where required to ensure the delivery of the strips in a flat condition to the various operating devices.

55 Toothed wheels 70 and 71 in loose mesh with each other are mounted beyond the heading device. The teeth 72 on the upper wheel are positioned to press alternate strips in the same direction out of the plane of the ribbon and this gives a staggered effect to the strips. Upper wheel 70 is slidably mounted on its shaft so that the staggering effect may be eliminated. Wheel 71 is driven from roller 68 by means of bevel wheels 73 and connecting shaft 74.

In the operation of the machine a ribbon of paper pulp board of any desired length, width, and thickness, is inserted between the rollers 20, 21 which deliver the ribbon between the splitting rollers 24, 25. As the ribbon enters the rollers adjacent faces of intermeshing teeth 26 shear the ribbon into strips transversely to the length of the ribbon, the rubber blocks resiliently support the ribbon during the shearing operation and force the strips out of the recesses as the teeth rotate out of mesh. The width of the ribbon is such that the cuts extend to one edge only leaving an uncut butt or stub 75 (Figs. 11, 12) of any desired length at the other edge of the ribbon to retain the strips as projecting tongues.

The ribbon is then driven between the crowning and ribbing rollers 39, 40 which form a convex boss 76 on one face of each strip and near its free end and form also a central longitudinal reinforcing rib 77 on each strip.

The ribbon is then passed to the liquid containing well 46 where the wheel 51 immerses the strips, but not the butt or stub, in the liquid. On leaving the well the strips are received by the perforating rollers 52, 53 which perforate each strip near the butt to facilitate removal. The perforated strips are then delivered to the heading device where each strip head receives a limited coating of heading material.

The sheet ribbon is then moved on to bring the strips into the staggering device which bends alternate strips in the same direction out of the plane of the ribbon.

Should it be desired to manufacture matches which are undipped, non-perforated, or non-staggered, wheel 51 is loosened and slid along its shaft out of contact with the strips and the well is covered. The shaft of perforating roller 52 may also be raised to prevent co-action with roller 53, and the upper wheel of the staggering device is loosened and drawn along its shaft out of contact with the lower wheel. The bosses 44 on roller 40 may also be removed so that only the rib 77 is formed and the crown 76 is not formed on each strip as it passes through the rollers 39, 40. In this case block 59 (Fig. 9) of the heading device is replaced by another block (Fig. 10) in which the delivery passage 65 supplies heading material to both of the broad faces of the free end of each strip.

I claim:—

1. A method of making matches from paper pulp board in which a ribbon of the board is fed between splitting rollers which shear the ribbon into match strips projecting from a stub on the ribbon, the split ribbon is passed between crowning and ribbing rollers which form a crown near the end of each strip and a longitudinal reinforcing rib on each strip, and then to a heading device which forms

a striking head near the free end of each strip.

2. A method of making matches from paper pulp board in which a ribbon of the board is fed between splitting rollers which shear the ribbon into match strips projecting from a stub on the ribbon, the split ribbon is passed between crowning and ribbing rollers which form a crown near the free end of each strip and a longitudinal re-inforcing rib on each strip, then to a dipping well in which each strip is coated with liquid, through perforating rollers which perforate each strip near the stub, to a heading device which forms a striking head on and about the crown on one face of each strip, and to a staggering device which bends alternate match strips in the same direction out of the plane of the ribbon.

3. A machine for making matches from paper pulp board having splitting rollers provided with intermeshing straight edged teeth of rectangular section, rubber blocks in the recesses between the teeth of each roller and having a metal plate secured to the outer face of each block, a crowning and ribbing roller having bosses and ribs projecting from its periphery and a co-acting roller having peripheral recesses positioned to register with the bosses and ribs of the crowning and ribbing roller.

4. A machine for making matches from paper pulp board having splitting rollers provided with intermeshing straight edged teeth of rectangular section, rubber blocks in the recesses between the teeth of each roller and having a metal plate secured to the outer face of each block, co-acting crowning and ribbing rollers having peripheral bosses and ribs on one roller and peripheral recesses on the other roller positioned to register with the bosses and ribs of the first roller, a liquid containing well and a wheel adapted to immerse in the liquid the strips received from the ribbing rollers.

5. A machine for making matches from paper pulp board having splitting rollers provided with intermeshing straight edged teeth of rectangular section, rubber blocks in the recesses between the teeth of each roller having a metal plate secured to the outer face of each block, co-acting crowning and ribbing rollers having peripheral bosses and ribs on one roller and corresponding peripheral recesses on the other roller, and a match heading block provided with a delivery passage for heading material and with a strip head receiving recess adapted to limit the quantity of heading material on each strip head.

6. A machine for making matches from paper pulp board having splitting rollers provided with intermeshing flat ended straight edged teeth of rectangular section, rubber blocks each faced with a metal plate in the

recesses between the teeth of each roller, co-acting crowning and ribbing rollers having registering projections and recesses on their peripheries, perforating rollers having a circumferential row of pins on the periphery of one roller and a corresponding circumferential groove on the other roller, and a match heading block with a delivery passage for heading material and with a strip head receiving recess adapted to limit the quantity of heading material on each strip head.

7. A machine for making matches from paper pulp board having splitting rollers provided with intermeshing straight edged teeth of rectangular section, rubber blocks each faced with a metal plate in the recesses between the teeth of each roller, co-acting crowning and ribbing rollers having registering projections and recesses on their peripheries, a liquid containing well, a wheel adapted to immerse in the liquid strips received from the ribbing roller, co-acting perforating rollers having a circumferential row of pins on the periphery of one roller and a registering circumferential groove on the other roller, and a match heading block having a delivery passage for heading material and a strip head receiving recess adapted to limit the deposit of heading material on each strip head.

8. A machine for making matches from paper pulp board having splitting rollers provided with intermeshing straight edged teeth of rectangular section and with rubber blocks in the recesses between the teeth of each roller and a metal plate secured to the face of each block, co-acting crowning and ribbing rollers having registering projections and recesses on their peripheries, a match heading block provided with a delivery passage for heading material and with a strip head receiving recess adapted to limit the quantity of heading material on each strip head, and co-acting staggering wheels adapted to bend alternate match strips received from the heading device.

9. A machine for making matches from paper pulp board having splitting rollers provided with intermeshing straight edged teeth of rectangular section and with metal faced rubber blocks in the recesses between the teeth in each roller, co-acting crowning and ribbing rollers provided with registering projections and recesses on their peripheries, a dipping well, co-acting perforating rollers having projecting pins on the periphery of one roller and a circumferential groove on the periphery of the other roller, a heading block provided with a delivery passage for heading material and with a strip head receiving recess to limit the quantity of heading material on each strip head, co-acting staggering wheels to bend alternate strips, and feeding rollers and guide plates for the

board positioned between the operative parts of the machine.

10. A method of making matches from paper pulp board consisting of splitting a ribbon of the board between toothed rollers, resiliently supporting the ribbon between the teeth of each roller, and shearing the ribbon into flat strips projecting in the plane of the ribbon transversely to the length of the ribbon from a stub.

10 11. A method of making matches from paper pulp board consisting of splitting a ribbon of the board between toothed rollers, resiliently supporting the ribbon between the teeth of each roller, shearing the ribbon into flat strips projecting in the plane of the ribbon transversely to the length of the ribbon from a stub, and forming a crown embossing near the free end of each strip.

20 12. A method of making matches from paper pulp board consisting of splitting a ribbon of the board between toothed rollers, resiliently supporting the ribbon between the teeth of each roller, shearing the ribbon into flat strips projecting in the plane of the ribbon transversely to the length of the ribbon from a stub, forming a crown embossing near the free end of each strip, and depositing striking material on said embossing.

30 13. A method of making matches from paper pulp board consisting of splitting a ribbon of the board between toothed rollers, resiliently supporting the ribbon between the teeth of each roller, shearing the ribbon into flat strips projecting in the plane of the ribbon transversely to the length of the ribbon from a stub, forming a crown embossing near the free end of each strip, depositing striking material on said embossing, and 40 forcing alternate match strips out of the plane of the ribbon.

In testimony whereof I have affixed my signature.

JOHN GLEN NEWMAN.
